UNITED STATES PATENT OFFICE.

CALVIN JACKSON, OF READING, PENNSYLVANIA.

DESIGN FOR A METAL-CUTTING TOOL.

SPECIFICATION forming part of Design No. 31,789, dated November 7, 1899.

Application filed September 18, 1899. Serial No. 730,943. Term of patent 14 years.

To all whom it may concern:

Be it known that I, CALVIN JACKSON, a citizen of the United States of America, and a resident of Reading, in the county of Berks and State of Pennsylvania, have invented and produced a certain new and original Design for a Metal-Cutting Tool, of which the following is a specification.

My invention relates to a design of metal-cutting tool.

Figure 1 is a side elevation, Fig. 2 a plan view, and Fig. 3 an end view, of my new design of metal-cutting tool.

The main or essential features of my design comprise a cylindrical shank portion *a* and an integral flattened cutter end *b* in the form of a comparatively thin and approximately

rectangular blade wider than the diameter of the shank *a* and attached to the latter to one side of the center line thereof, said blade ²⁰ having its forward edge *c* out of perpendicular with the axis of the cylindrical shank and its maximum thickness at the outermost corner *d*.

What I claim is—

The design for a metal-cutting tool substantially as shown and described.

Signed by me at Reading, Pennsylvania, this 15th day of September, 1899.

CALVIN JACKSON. 25
